UNITED STATES PATENT OFFICE.

BRADFORD A. THOMAS, OF SAN FRANCISCO, CALIFORNIA.

HYDROCARBON-BURNER.

1,092,308.

Specification of Letters Patent. Patented Apr. 7, 1914.

Application filed July 25, 1913. Serial No. 781,195.

To all whom it may concern:

Be it known that I, BRADFORD A. THOMAS, a citizen of the United States, residing at San Francisco, in the county of San Francisco and State of California, have invented 5 certain new and useful Improvements in Hydrocarbon-Burners, of which the following is a specification; reference being had therein to the accompanying drawing.

10 This invention relates to a hydro-carbon burner and the principal object of the invention is to provide a novel arrangement of parts whereby the burner will be caused to operate very efficiently and the starting 15 of the burner facilitated.

Another object of the invention is to so construct the burner that a good draft may be provided through the drip pan.

Another object of the invention is to provide the drip pan with a plurality of openings above which troughs are placed so that the burner pipe may be supported above the sand in the drip pan directly above the draft opening in the pan.

25 With these and other objects in view, this invention consists of certain novel combinations, constructions and arrangements of parts as will be hereinafter fully described and claimed.

30 This invention is illustrated in the accompanying drawings, wherein:

Figure 1 is a side elevation of the stove provided with the improved burner. Fig. 2 is a view showing the fire box of the stove 35 in vertical section and the burner partially in elevation, and partially in section. Fig. 3 is a section taken along the line 3—3 in Fig. 2. Fig. 4 is a section taken along the line 4—4 in Fig. 3. Fig. 5 is a sectional 40 view through the nozzle and a portion of its feed pipe. Fig. 6 is a perspective view of the deflector plate. Fig. 7 is a plan view of the drip pan with the sand removed. Fig. 8 is a perspective view of the supporting 45 trough.

In the accompanying drawings the numeral 10 indicates the stove which is provided with the fire box 11 having the usual grate 12 and openings which are normally 50 closed by the cover plate 13. This stove may be used with coal, but it is desired to provide an arrangement whereby oil may be

burned in the fire box when it is not desired to use coal as fuel. This improved oil burner has, therefore, been provided and 55 will now be described in detail.

The oil is stored in a receptacle 14 having a pipe 15 leading therefrom and provided with a control valve 16 by means of which the flow of oil through the pipe 15 can be 60 regulated or stopped entirely, if desired. This pipe 15 is connected with the pipe 17 by means of the elbow 18 and this pipe 17 forms what I shall call the oil main 65 since the oil is led from this pipe by means of branch pipes 19 and 20 to the burner pipes. These pipes 19 and 20 are connected with the main by means of valves 21 and 22, the valves being provided so that the flow of oil through the pipes 19 and 20 can be 70 independently regulated or if desired the flow of oil through one of the pipes can be entirely cut off without the flow through the other pipe being affected. When both of the valves 21 and 22 are open the oil can 75 flow through the two pipes 19 and 20 thus permitting both of the burners to be operated until the fire box is well heated. It is not necessary to burn both of the burners unless food is being cooked over both of 80 the openings in the top of the stove, and therefore one of the valves can be closed, thus shutting off the supply of oil to the burner.

The burners which are connected with the 85 pipes 19 and 20 are identical in construction, and, therefore, a description of one of these burners will be sufficient for both burners. The branch pipe is provided with a coupling 23 communicating with a lead 90 24 which lead pipe communicates with the generating chamber 25 by means of the elbows 26 and 27 which are connected by the nipple 28. It should be noted that the elbow 27 is enlarged at its upper end so 95 that the oil in the pipe 24 will be prevented from entering the generating chamber with too great speed. This prevents the oil from passing through the generating chamber too rapidly and thus gives the oil sufficient 100 time to be thoroughly heated and turned into gas before leaving the generating chamber. It should be noted that the lead 24 extends substantially parallel to the gen-

erating chamber 25 and not far from a point beneath the generating chamber so that the lead will be heated, and thus the oil partially heated before entering the generating chamber. The generating chamber communicates with a tapered elbow 29 which elbow has a tendency to increase the force of gas generated in the generating chamber so that the gas will flow rapidly through 10 the pipe 30 and elbow 31 into the burner pipe 32 and out through the nozzle 33. The nozzle 33 is provided with a small outlet opening 34 as shown in Fig. 5, and the heated gas will, therefore, pass through this 15 opening with a great deal of force, thus carrying with it a great deal of oil which has not been sufficiently heated to form gas. This gas and oil will be driven upwardly, as shown in Fig. 2 and will strike 20 a deflector plate 35 mounted on the generating chamber and adjustably held in place by the ring 36. When the gas strikes the deflector plate it will be thrown in all directions and the flame will thus spread out 25 and thoroughly heat the generating chamber and lead pipe 24.

The grate 12 forms a support for a drip pan 37 which pan rests upon the grate as shown in Fig. 2 and is provided with openings 38 and 39 positioned beneath the troughs 40 and 41 which troughs are provided with supporting feet 42 holding them in spaced relation above the openings 38 and 39. These troughs are surrounded by sand 35 or any other suitable substance which will absorb oil and form supports for the burner pipes and nozzles of the burners. The trough not only forms a support for the burner pipe, but also provides means for 40 holding the nozzles beneath the deflector plate 35 since the collars 43 of the nozzles 33 rest in the troughs and thus prevent the burner pipes from moving transversely in the fire box.

45 The operation of this burner is as follows: The valve 16 is opened and the valves 20 and 21 are then opened and left on until the oil flows out of the nozzles 33 into the troughs 40 and 41 and over into the sand 50 in the drip pan 37. The valves 21 and 22 are then closed and the match is then applied to the sand so that the oil in the sand will be ignited. This oil is burned and will heat the burner until the oil in the pipes 55 24, 25, 30, and 32 is converted into gas. It will also heat the oil unassisted as soon as the oil in the trough is converted into gas. The gas and heated oil will be driven out through the small openings 34 into the nozzles 33 and will strike the deflector plates 35. The valves 21 and 22 will then be opened 60 again, thus permitting the oil to feed into the lead 24 and from this pipe into the generating chamber 25. As soon as the fire box

is well heated one of the valves 21 or 22 65 can be shut off and the remaining burner will be sufficient to heat the fire box at the desired temperature. Of course, if it is desired to cook from both the openings in the stove cover the two burners may be left in 70 operation.

A burner has thus been provided in which the oil is first heated in the lead 24 and then passed into the generating chamber 25 at a reduced speed due to the enlarged elbow 27 75 after which it is passed into the pipe 30 at an increased speed due to the tapered elbow 29. The gas and heated oil pass through the pipe 30 into the burner pipe 32 and pass out through the nozzle 33 at a greatly increased speed due to the relative size which the opening 34 bears to the interior of the pipe 32. The burner has also been greatly improved since the oil in the trough is heated when the oil which flows into the sand 80 is burned, thus causing the oil in the pipes to be converted into gas at the initial lighting of the burner. The trough not only forms a receptacle for oil, but also forms means for supporting the burner pipe 32 and 85 prevents it from moving transversely in the fire box.

What is claimed, is:—

1. A burner comprising an oil main, branch pipes, valves connecting said branch pipes with said oil main, a drip pan provided with openings in its bottom, troughs positioned in said drip pan and located above the openings in the bottom of the pan, absorbent material in said drip pan surrounding said troughs, lead pipes leading from said branch pipes, generating chambers connected with said lead pipes and positioned to one side of said lead pipes and in a higher plane than said lead pipes, conductor pipes extending downwardly from said generators, burner pipes connected with said conductor pipes and extending into said troughs, nozzles carried by said burner pipes and resting in said troughs, said nozzles being provided with collars engaging the sides of said troughs to prevent said burner pipes from moving out of a normal position, and deflector plates carried by said combustion chambers and positioned above the outlets of said nozzles whereby a stream of combustible fluid passing from each of said nozzles will strike one deflector plate whereby the flame will heat said generating chamber and will also heat said lead pipe. 110

2. A burner comprising an oil main, a branch pipe leading from said oil main, a control valve for said branch pipe, a lead pipe leading from said branch pipe, a generating chamber connected with said lead pipe, a burner pipe positioned beneath said generating chamber and connected therewith, a drip pan, a trough in said drip pan, 115

a nozzle for said burner pipe fitting within
said trough and engaging the side walls
thereof to prevent transverse movement of
said burner pipe, and a deflector carried by
5 said generating chamber and positioned
above the outlet nozzle of said burner pipe.

In testimony whereof I hereunto affix my
signature in presence of two witnesses.
